GAME APPARATUS

Einar Wilhelm Larsson-Letzén, Malmö, Sweden

Application October 6, 1936, Serial No. 104,219
In Great Britain February 18, 1936

5 Claims. (Cl. 273—85)

The present invention relates to a game apparatus, particularly adapted to be played to simulate a football contest or the like. The game device comprises a plate having a plurality of playing members thereon, which are mounted to be rotated about substantially vertical axes.

The main object of the invention is to provide playing members having arms of such a length as to make the areas traversed by the arms of two adjacent playing members, when rotated, partially coincide.

An embodiment of the invention will be described below with reference to the accompanying drawing, in which

15 Fig. 1 is a plan view of the game device,
Fig. 2 is a sectional view on the line II—II of Fig. 1, and

20 Figs. 3 and 4 are detail views showing modified embodiments of parts of the playing members on a larger scale, Fig. 4 being a sectional view on line IV—IV of Fig. 3.

Figs. 5 and 6 are detail views showing modified embodiments in which vertically flexible arms are employed.

25 According to Figs. 1 and 2, a horizontally positioned plate 1 is provided on its lower surface with supports 6 and on its upper surface with a play ground 2 framed by longitudinal ribs 3 and transverse ribs 4. The centre portions of the transverse ribs 4 are removed and replaced by goals 5 provided with movable goal keeper members of any suitable type.

30 Playing members A—F provided with shafts 10 are rotatably mounted in vertical bushings 11 in the plate 1 and equipped with substantially horizontal arms 12 having substantially horizontal projections 13, 14, 15 thereon. The distance between projections 14 and 15 of an arm 12 is somewhat in excess of the length of the diameter of a playing ball 16, and this also preferably applies to the distance between projections 13, 14 of two adjacent playing members, when facing each other as at B and C.

35 The arm 12 has an extension 12a of a length to place the outer end thereof approximately in a vertical plane through the projection 15 of an adjacent arm when the two arms are in the relative position shown at B and C in Fig. 1. In the embodiment shown in Figs. 1 and 2, the extension 12a lies in the same horizontal plane as the arm 12, and in this case some of said arms 12 will have to be positioned at another height above the play ground 2 than the others, so as to enable the first-mentioned arms, when rotated, to pass below or above the last mentioned ones.

In the drawing said extensions 12a comprise thin metal strips.

A third embodiment of said arms is illustrated in Figs. 5 and 6. In this case the arms 12 and extensions 12a are all in one and the same horizontal plane, the arms 12, or at least the extensions, being flexible vertically in order to enable two arms, or extensions, when engaging each other, to be bent upwards or downwards and thus pass each other. To facilitate this procedure, the extensions are suitably provided with sharp edges, as shown in Fig. 6.

In Fig. 3 a modified embodiment of the arms 12 and their extensions 12a is illustrated. In this embodiment the arms 12 are positioned at one 15 and the same height, the extensions 12a, on the other hand, being placed at different heights above said arms 12, and attached to those arms between the projections 15 and the axes of rotation of said arms.

20 The shafts 10 are rotated by means of cranks 22—25 connected to vertical shafts 21 positioned outside the frame ribs 3, 4. Said shafts 21 are operatively connected with the shafts 10 below the plate 1 by lines or the like 28 acting upon grooved wheels or the like 20 and 26 secured to the shafts 10 and 21, respectively. As indicated by dotted lines in Fig. 1, playing members B, D, and F are manipulated by the cranks 22 and 24, playing members A, C, and E being manipulated by the cranks 23 and 25 positioned at the opposite end of the plate 1. Naturally, the playing members may be manipulated by other known means, or each playing member may be individually manipulated by a separate crank or other suitable means.

25 By suitably rotating and stopping cranks 22—25 the ball 16 may be caught inside one of the projections 13 and 15 or between projections 14 and 15 and forcibly pushed in any desired direction. 40 On the other hand, when the ball is caught by any of the projections 13 or 14 the opposing player may steal it by means of the extension 12a of an adjacent arm 12. Every point of the play ground 2 lies within the area of operation of the 45 playing members.

30 In order to enable the players, if desired, to lift the ball from the play ground and to send it flying through the air past one or more playing members barring the way, the arms may be provided, 50 preferably between projections 14 and 15, with means, such as horizontal or inclined plates 30 or 31, Fig. 4, threads or the like, acting upon the lower fourth of the ball 16.

35 The invention is not limited to the specific 55

embodiments shown but various deviations may be made therefrom without departing from the spirit and scope of the appended claims.

I claim:—

- 5 1. In a game apparatus particularly for simulating a football contest and similar contests, a plate having a substantially horizontal position so as to form a play ground, a plurality of playing members mounted in bearings at different points 10 of said play ground so as to be rotatable about substantially vertical axes, substantially horizontal arms connected to said playing members, lateral projections on said arms of such an arrangement and shape as to prevent a ball trapped 15 inside one of said projections from rolling radially outwards along said arm.
2. A game apparatus as in claim 1, further characterized by means attached to said arms and adapted together with the arm, when hitting the ball, to lift it from the play ground and send it 20 flying through the air.
3. In a game apparatus particularly for simulating a football contest and similar contests, a plate having a substantially horizontal position 25 so as to form a play ground, a plurality of playing members mounted in bearings at different points of said play ground so as to be rotatable about substantially vertical axes, substantially horizontal arms connected to said playing members, lateral projections on said arms of such an arrangement and shape as to prevent a ball trapped 30 inside one of said projections from rolling radially outwards along said arm, and extensions on said arms, the extensions of adjacent arms overlapping each other at different levels so as to play 35 partly over the same area and freely pass each other at any time.

4. In a game apparatus particularly for simulating a football contest and similar contests, a plate having a substantially horizontal position so as to form a play ground, a plurality of playing members mounted in bearings at different points of said play ground so as to be rotatable about substantially vertical axes, substantially horizontal arms connected to said playing members, lateral projections on said arms of such an arrangement and shape as to prevent a ball trapped 10 inside one of said projections from rolling radially outwards along said arm, means attached to said arms adapted together with the arm, when hitting the ball, to lift it from the play ground and send it flying through the air, and 15 extensions on said arms, the extensions of adjacent arms overlapping each other at different levels so as to play partly over the same area and freely pass each other at any time.

5. In a game apparatus particularly for simulating a football contest and similar contests, a plate having a substantially horizontal position so as to form a play ground, a plurality of playing members mounted in bearings at different points of said play ground so as to be rotated 20 about substantially vertical axes, substantially horizontal arms connected to said playing members, means attached to said arms adapted together with the arm, when hitting the ball, to lift it from the play ground and send it flying 25 through the air, and extensions on said arms, the extensions of adjacent arms overlapping each other at different levels so as to play partly over the same area and freely pass each other at any time.

EINAR WILHELM LARSSON-LETZÉN.
